ALEXANDER MURRAY, OF SPRINGFIELD, MASSACHUSETTS.

ART OF MAKING VARNISH.

Application filed August 12, 1921. Serial No. 491,772.

To all whom it may concern:

Be it known that I, ALEXANDER MURRAY, a subject of the King of Great Britain, residing at Springfield, in the county of 5 Hampden and State of Massachusetts, have invented new and useful Improvements in the Art of Making Varnish, of which the following is a specification.

The present invention relates to the art 10 of making varnish and more particularly to the manufacture of tung varnishes in which China wood oil is combined with resins which are easily fused such, for example, as common rosin or dammar.

15 Tung varnishes are ordinarily produced by mixing common rosin and China wood oil, heating the mixture to a high temperature and then diluting it with solvents. Usually the rosin is first treated by combining it 20 with lime or glycerine to neutralize the acid and harden the rosin. Then the China wood oil is added and the mixture heated to a temperature of 400 to 550° F., for varying lengths of time, then cooled down to a temperature of 350 to 400° F., after which the 25 diluent or solvent is added. The mixture is then clarified and pumped into a storage tank. The practice of the above described method involves the use of cumbersome apparatus and the expenditure of an amount of 30 time and labor, entirely disproportionate to the quantity of the product obtained, and consequently the cost of production is high.

One of the objects of the present invention 35 is to provide an improved method of producing varnish which may be carried on continuously, thereby effecting a great saving in time, labor and material.

Another object of the invention is to provide 40 an apparatus for the continuous manufacture of varnish.

To the accomplishment of these objects and such others as will hereinafter appear, the invention consists in the process and apparatus hereinafter described and claimed, 45 the advantages of which will be obvious to those skilled in the art.

The invention will be best understood from the following description taken in connection 50 with the accompanying drawings illustrating an apparatus constructed in accordance therewith.

In the drawings,—

Fig. 1 is a diagrammatic view of the entire apparatus in what is at present considered to be its preferred form;

Fig. 2 is a longitudinal sectional view of the cooking tank and certain associated parts; and

Fig. 3 is a detail perspective view of a portion of the cooking tank.

In the illustrated apparatus, a pulverized resin, such as common rosin is mixed with lime and preheated until the rosin is melted. The melted rosin, together with the lime, is 60 then introduced into one end of a cooking receptacle or tank 5. The cooking tank is constructed with a plurality of transverse partitions arranged to provide a long tortuous passage through which the substances 65 to be treated are caused to flow in a slowly moving continuous stream while they are being heated or "cooked." As the melted rosin, and the lime carried thereby, flows slowly through the tortuous passage at the 70 receiving end of the cooking tank, the temperature of the moving mass is maintained at, say 450 to 550° F. for a substantial period of time during which the lime chemically combines with the rosin, the reaction being 75 mechanically assisted by means of suitable agitators in the cooking tank which thoroughly stir up the mixture. At the expiration of this heating period, the flow of the rosin has progressed through somewhat less 80 than one third the length of the tank 5. At this point in its flow, a preheated drying oil such as China wood oil is introduced into the stream of heated and chemically combined rosin and lime. As the rosin and oil 85 flow onward through the tortuous passage of the cooking tank they become thoroughly intermixed and cooked so as to produce a so-called varnish "body" or "base." Before leaving the cooking tank the varnish body is 90 cooled to a sufficiently low temperature to enable the thinning or blending operation to take place. For this purpose, the varnish body passes into a blending chamber 6 where a suitable solvent such as benzine is added, 95 to dilute the varnish body to the desired consistency, the blending operation being facilitated by a suitable agitator in the blending chamber. The varnish thus produced is then clarified by means of a centrifugal clarifier 7 from which it is drawn off by a pump 8 and delivered by the latter 100 into the storage tank 9.

In the manufacture of varnish, as above described, the varnish materials are continuously supplied at different points 110 throughout the length of the apparatus so

- as to provide for a continuous flow through the apparatus of the materials being treated. Thus, although many of the steps of the process occur progressively as the substance 5 acted upon flows through the apparatus, all of these steps are continuous and are being concurrently performed at different points along the path of movement of the slowly flowing stream of material.
- 10 To provide the desired tortuous passage through the cooking tank for the varnish materials, a series of vertically disposed partitions, alternately designated at 10 and 11 in Fig. 2, extend transversely across the tank.
- 15 The partitions 10 are positioned with their lower ends somewhat above the floor of the tank, thus providing the ports 12 through which the fluid may flow from one side of said partitions to the other. The partitions 20 11 fall short of extending to the top wall of the tank so that the fluid in the tank may flow over the top edges thereof into the sections of the tortuous passage which are formed between said partitions and the partitions 25 10 immediately in advance thereof. The partitions 11 also fail to reach the top wall of the tank but they rise somewhat higher than the partitions 10 to prevent passage of the fluid across the top edges thereof.
- 30 In order to cause a flow by gravity of the liquid from one end of the tank to the other, the tank is inclined downwardly toward the rear or delivery end thereof. With the above described construction and arrangement 35 of the portions of the tank, a continuous tortuous passage is provided throughout the length of the tank. The flow of the varnish material is continuous through this passage, the liquid flowing downwardly 40 through the passage sections at the left of each partition 10, through the ports 12, then upwardly through the passage sections at the right of each partition 10 and then over the top edges of said partitions and 45 down on the advance sides thereof.

The heating of the rosin and lime, within the cooking tank 5, and the initial cooking of the varnish body are effected by the continuous application of heat to the exterior 50 of the cooking tank. This heating of the rosin and lime may continue throughout a period of approximately half an hour while the initial cooking of the varnish body may continue from, say 20 to 40 minutes. At 55 the expiration of the initial cooking period, the varnish body reaches a point substantially at the middle of the tortuous passage through the cooking tank. Throughout the remainder of its progress through the cooking tank there is no further external application 60 of heat to the varnish body and the cooking process is continued solely by the action of the heat retained within the substance being cooked, the radiation of heat 65 therefrom being prevented by suitable in-

sulation of the walls of the cooking tank as indicated in a conventional manner in Fig. 2. All flues and conduits through which heated material is permitted to pass, are also insulated in a well known manner, 70 but it is not considered necessary to indicate such insulation in the drawings.

It will be apparent from the above description that three distinct operations are carried out in the cooking tank, first the 75 heating and stirring of the rosin to cause it to combine with the lime; second, the cooking of the intermingled rosin and the drying oil to produce the varnish body; and, third, the cooling of the varnish body preparatory 80 to introducing it into the blending tank. The cooking operation is divisible into two stages, first, the cooking by the application of external heat, and second, the cooking by means of the heat retained within the substance being cooked, the latter stage being similar to the ordinary fireless cooker process. For convenience of description, therefore, the cooking tank may be regarded as 85 consisting of the following sections; first, the section 13 (Fig. 2) in which the rosin is heated; second, the section 14 in which the cooking of the varnish body is started by the external application of heat; third, the section 15 in which the cooking operation is 90 completed by the heat retained within the varnish body; and fourth, the section 16 where the varnish body is finally cooled.

Heat is externally applied to the cooking tank 5 from any suitable source such as a 100 gas, oil, coal, or coke burner. In the illustrated apparatus, an oil burner is indicated at 17, the burner being installed in a heating chamber 18 and fed through a supply pipe 19. The heated gases from the chamber 18 are led through a flue 20 to a heating jacket 22 which encloses the two opposite sides and the bottom of the section 14 of the cooking tank. The heating jacket 22 (Fig. 3) is divided by a series of partitions 23 to 105 provide a plurality of U-shaped passages 24 which are arranged side-by-side to entirely surround the bottom and the opposite sides of the cooking tank section 14. The heated gases pass from the flue 20 into the upper portion of one of the U-shaped jacket passages 24 at one side of the cooking tank. As best shown in Fig. 3, the several passages 23 are successively interconnected by means of ports 25, these ports being located at the upper ends of the passages and the ports in adjacent passages being arranged at opposite sides of the tank. By this arrangement the gases are conveyed in a tortuous path winding back and forth from one side of the tank to the other to produce a continuous flow from the flue 20 to the rear end 110 of the jacket 22.

After reaching the rear extremity of the tortuous passage through the heating jacket 115

22 the still hot gases leave this jacket through a conduit 26 by which they are conducted to a heating jacket 28, communication between the conduit 26 and the heating jacket 28 being established through a short pipe 27. The jacket 28 is independent of the jacket 22 and is subdivided by a portion 29 into two U-shaped sections or passages 30 which together surround the bottom, the opposite sides, and the front end of the section 13 of the cooking tank. The pipe 27, leading from the conduit 26, opens into the upper end of the rearmost of the passages 30 at one side of the tank while the upper end of said passage, at the opposite side of the tank, communicates through a port 31 with the adjacent or end passage 30. From the end passage 30 the gases, which are still hot, pass outwardly and upwardly through a conduit 33 and thence through a jacket 34 where they serve to melt the rosin prior to its introduction into the cooking tank. At the front end of the cooking tank, an inclined U-shaped partition 35 is located near the outlet conduit 33 and partially blocks the passage 30. The partition 35 deflects the current of outgoing gas so as to prevent the trapping of gas in the upper portion of said passage. From the jacket 34 the gases pass into a flue 37 communicating with an exhaust flue 38 (Fig. 1). The gases are drawn through the above described system of flues and heating chambers by forced draft produced by a centrifugal fan 40 that is located in the upper portion of the exhaust flue 38.

When the gases reach the heating jacket 28, which surrounds the front end of the cooking tank, more or less heat has been abstracted therefrom. In order to provide for the application of a sufficient amount of heat to the front end of the cooking tank to insure the proper heating of the rosin, provision is made for discharging an additional supply of hot gas into the heating jacket 28 through an auxiliary flue 42 which leads directly from the heating chamber 18 to the pipe 27 through which the gas may pass into the heating jacket 28.

To provide for an even maintenance of the required degree of temperature in the heating jacket 22, provision is made for automatically increasing or diminishing the intensity of the heat in the chamber 18. To this end, a thermostat 44 projects into the section 14 of the cooking tank and said thermostat is arranged to control a valve 45 controlling the flow of the fuel oil through the supply pipe 19 to the burner 17. In this way the intensity of the source of heat may be varied according to the requirements in the jacket 22.

A similar provision is made for regulating the supply of additional heat through the flue 42 to the jacket 28. For this purpose

a by-pass 46 rises from the auxiliary flue 42 at the point where said flue enters the jacket 28, the by-pass extending above the cooking tank and being connected with the exhaust flue 38. A valve 47 is provided in the by-pass 46 and a thermostat 48 is projected into the section 13 of the cooking tank and is connected to control said valve. Thus, if the temperature of the substance within the section 13 of the cooking tank falls below a predetermined degree the thermostat 48 will operate to close the valve 47 and check the passage of the gas through the by-pass 46 so that a greater amount of it will enter the heating jacket 28. If, on the other hand the temperature in the section 28 of the cooking tank rises above a predetermined degree, the valve 47 will be opened by the action of the thermostat 48, thus permitting more gas to flow through the by-pass 46, with the result that less gas will enter the heating jacket 28. In this way a constant temperature at a required degree may be automatically maintained in the heating jacket 28.

The pulverized rosin, together with the necessary amount of lime, is deposited in a hopper 50, the supply being replenished from time to time as occasion requires. The rosin is fed from the bottom of the hopper 50, through a downwardly inclined tube 51, by means of a screw-conveyer 52 rotatably mounted within the tube 51 and provided with a pulley 53 by means of which it may be driven. The conveyer tube 51 extends through the heating jacket 34 hereinbefore referred to and the rosin is preheated during its passage through said tube so that it is melted by the time it reaches the lower end thereof. The melted rosin is discharged from the tube 51 through a nozzle 54 into the front end of the section 13 of the cooking tank 5, and at the top of the latter.

After the melted rosin has reached the cooking tank it flows slowly through the section 13, passing downward and upward through the tortuous passage therein. During its flow through the section 13, the lime contained within the rosin combines chemically with the molten rosin, the reaction between the lime and rosin being mechanically brought about by the heat and the stirring action of the two agitator devices 57, the latter comprising rapidly rotating blades which are located near the bottom of the tank. As shown, the agitator blades are carried at the lower ends of vertical stems 58 which are journaled at their upper ends in bearings upon the top of the tank and are provided with pulleys 59 by which they may be driven.

The present apparatus is adapted to permit the use of glycerine instead of lime for neutralizing the rosin. In using glycerine, it is introduced into the section 13 of the cooking tank through an inlet pipe 60 which

extends nearly to the bottom of the tank and delivers the glycerine directly into the field of operations of the first agitator device 57. The China wood oil, or other drying oil, 5 is intermixed with the rosin as the latter flows into the section 14 of the cooking tank where the initial cooking operation takes place. The drying oil is supplied from a reservoir 64 and feeds by gravity from the 10 bottom of the reservoir through a conduit 65 which conveys it to the cooking tank. To insure the feeding of the oil at a constant pressure irrespective of variations of the liquid level in the reservoir 64, a suitable 15 float valve 66 is provided, the latter having a float chamber 67 in which a constant level of the oil is maintained. From the float chamber 67, the drying oil is led by the conduit 65 through a meter 68 and thence 20 through a heating chamber 69, in which the oil is preheated, said chamber being formed by an enlargement of the exhaust flue 38, and the oil conduit extending through said chamber in the form of a coil 70. From the 25 coil 70, the preheated oil is led through a continuation of the conduit 65 to a union 71 where a conduit 72 of smaller capacity than the conduit 65 leads from the latter conduit to a coil 73 in the section 16 of the cooking 30 tank. As shown in Fig. 2, the convolutions of the coil 73 extend vertically back and forth through the several sub-divisions of said section of the cooking tank. The conduit 72 continues beyond the coil 73, extending 35 upwardly through the top of the cooking tank at 74.

Although the oil in the coil 73 has been preheated, its temperature is still considerably below that of the varnish body when 40 the latter reaches the section 16 of the cooking tank. Consequently as the oil flows through the coil 73 it extracts heat from the varnish body, cooling it to a sufficiently low temperature to permit the blending or thinning operation to take place without raising the temperature of the diluent or solvent above the boiling point of the latter with the resulting loss of the solvent through vaporization. In passing through the coil 73, the 45 temperature of the oil is raised somewhat by the heat extracted from the varnish base and the oil is now at the proper temperature for mixing with the rosin. After leaving the coil 73, the oil passes through a continuation 50 of the conduit 72, through a valve 75, and thence forwardly through said conduit above the top of the cooking tank. Above the section 14 of the cooking tank, the conduit 72 is bent downwardly at 76 and delivers its 55 oil into the front end of said section.

The temperature of the varnish body prior 60 to the thinning operation is determined, as above explained, by the cooling coil 73 and this temperature is automatically regulated 65 by the valve 75 which controls the flow of

oil through said coil. To this end, the valve 75 is adapted to be operated by a thermostat 77 which projects into the section 16 of the cooking tank. To provide for the delivery of a constant volume of oil to the cooking 70 tank irrespective of variations in the flow of oil through the coil 73, a by-pass 78 connects the conduit 72 with the conduit 65, the by-pass connecting with the latter at the union 71. A manually operable valve 79 75 controls the flow through the by-pass 78, supplementing the supply of oil from the conduit 72 to a greater or less extent as may be required.

As the varnish materials flow through the 80 cooking tank, fumes and vapors arise therefrom into the space between the stepped liquid levels and the top of the tank. The vapors arising from the rosin in the section 85 13 of the tank contain more or less steam, whereas the fumes arising from the liquid throughout the rest of the tank are free from steam or water vapor. To prevent the steam from intermixing with the other vapors when the latter are drawn off at the 90 delivery end of the tank, as will be herein-after explained, the vapor space at the top of the tank is divided into two separated chambers or passages 82 and 84 by means of a partition 85 which extends downwardly 95 from the top of the tank to a point below the liquid level. The steam and other vapors in the chamber 82 are permitted to pass off through an outlet flue 86 leading from the chamber 82. The fumes which collect in 100 the chamber or passage 84 are exhausted therefrom through a flue 88 the latter leading from an extension 89 of the chamber 84 and being connected with the flue 38 above the fan 40.

The varnish body, after being cooled by the oil in the coil 73 to the proper temperature for contact with the solvent, flows downward through a short pipe 90 and discharges therefrom into the top of the blending tank 110 6. The benzine or other solvent is continuously supplied to the top of the tank by means of a conduit 92 leading from a supply reservoir 93. The solvent feeds by gravity 115 from the reservoir 93 to the blending tank. To insure the delivery of the solvent at a constant pressure, irrespective of variations of liquid level in the reservoir 93, there is provided in the conduit 92, a float valve 94, the latter being similar in construction and mode of operation to that of the float valve 66 already described. A meter 95 is also provided in the conduit 92 to indicate and record the quantity of solvent flowing 120 through the conduit.

The varnish body and the solvent are intermixed by the action of the agitator blades 96 so as to thoroughly incorporate the solvent into the varnish body. The agitator blades are located at the bottom of the blend- 130

ing tank, and are carried at the lower end of a vertical stem 97, which may be journaled in the top of the tank and rotated in any suitable manner as by means of a pulley 98 carried by a driving shaft 99 that is geared to the stem 97.

The vapor produced by the admixture of the varnish body and the solvent escapes into the flue 88 through the pipe 90 and the 10 chamber 89, the vapor flowing above and counter to the stream of varnish body issuing from the cooking tank. As the vapors from the blending tank rise through the flue 88 they condense upon the walls of the 15 flue and flow back through the chamber 89 and pipe 90 into the blending tank so that there is practically no loss of the solvent through vaporization. Inasmuch as the 20 steam which is produced at the front end of the cooking tank is prevented from passing into the flue 88 with the other fumes from the cooking tank, there is no possibility that water of condensation will be introduced 25 into the blending tank.

From the blending tank, the varnish produced by the thinning of the varnish body is lead through a conduit 100 to the centrifugal clarifier 7 which may be of any well known commercial construction. After 30 being clarified, the varnish is drawn from the clarifier through a pipe 101 by means of the pump 8 which forces the varnish upwardly through a pipe 102 and finally delivers it to the storage tank 9.

The practice of the process herein set forth and the use of the apparatus above described results in the continuous manufacture of varnish. Thus, although the 40 various steps of the process occur progressively and in the proper sequence, relatively to any particular portion of the stream of varnish materials, all the steps nevertheless take place concurrently and continuously throughout the operation of the apparatus employed. Consequently no portions of the 45 apparatus are at any time idle and a maximum yield is obtained. The initial cost of installation is very low in proportion to the quantity of the product produced, the illustrated apparatus being capable of producing 50 a quantity of varnish equal to that produced by an ordinary six fire varnish plant.

The above described provision for the distribution of heat to the different parts of 55 heating jackets surrounding the cooking tank effects the conservation of heat, while the recovery of the solvent by condensation of its vapors, effects a further economy in the operation of the device. Preferably, the 60 cooking tank is constructed partly or wholly of aluminum, glass or silica which have been found to insure the cooking of the varnish materials substantially, if not entirely, without discoloration. The paleness of the 65 product is further insured by cooking the

rosin in a chamber from which air is excluded. Furthermore by reason of the fact that there is no possibility of flame coming in contact with the varnish material or fumes at any point in the travel of the latter, there is absolutely no fire risk attendant upon the operation of the illustrated apparatus whereas in the forms of apparatus ordinarily employed the fire risk is high.

In operation, all of the steps except the 70 replenishment of the supply receptacle being automatic, a great saving of time and labor is effected. The proper temperature in the different parts of the cooking tank is automatically maintained by controlling the flow of the fuel oil through the supply pipe 19 and the rate of flow of the heated gases through the by-pass 46. The rate of flow of the drying oil is also automatically 80 regulated to control its rate of delivery to the cooking tank as well as to control the temperature of the varnish body as it leaves the cooking tank by controlling quantity of oil flowing through the cooling coil. Thus 85 very little supervision of the process is 90 necessary.

The improved process having been explained in connection with a description of the apparatus by means of which it is practiced, what is claimed as new is:

1. The method of making varnish which 95 comprises intermixing a resin and a drying oil, passing the mixture through a conduit, applying heat to the mixture to cook it as it passes through the conduit thereby producing a varnish body, and thinning the varnish body.

2. The method of making varnish which 100 comprises intermixing a resin and a drying oil and passing the mixture through a conduit, cooking the mixture as it passes through said conduit to produce a varnish body, cooling the varnish body before it leaves said conduit, and then diluting the varnish body with a solvent.

3. The method of making varnish which 105 comprises preheating a resin and a drying oil, intermixing the preheated materials and passing them through a conduit, applying heat to the mixture in the conduit to cook it as it passes therethrough thereby producing a varnish body, and thereafter thinning the varnish body.

4. The method of making a varnish body 115 which comprises intermixing a resin and a drying oil, passing the mixture through an elongated conduit, and applying heat to the mixture to cook it as it passes through the conduit.

5. The method of making varnish which 120 comprises passing a resin together with a neutralizing agent through a conduit, heating and agitating said materials as they pass through a portion of the conduit to bring about a reaction between them, introducing 125

- 6
- a drying oil into said conduit at a point in advance of said portion and causing it to pass through the rest of the conduit together with the other material therein, cooking the oil and the combined resin and neutralizing agent as said materials pass through the conduit thereby producing a varnish body, and diluting the varnish body.
7. The method of making varnish which comprises passing a quantity of varnish body through a conduit, cooking the varnish body adjacent the entrance end of said conduit by the application of heat thereto, continuing the cooking operation by preventing the radiation of heat from the varnish body as the latter continues to flow through the conduit, and diluting the cooked varnish body with a solvent.
8. The method of making varnish which comprises passing a quantity of varnish body through a conduit, cooking the varnish body adjacent the entrance end of said conduit by the application of heat, continuing the cooking operation by preventing the radiation of heat from the varnish body as the latter continues to flow through the conduit, cooling the moving current of varnish body, and thereafter diluting the varnish body with a solvent.
9. The method of making varnish which comprises introducing a melted resin together with a neutralizing agent into a conduit through which material may flow by gravity, and continuously during the passage of said material through the conduit, supplying a drying oil to the conduit, heating the conduit to cook the substance therein so as to convert it into a varnish body, and collecting the varnish body as it is continuously discharged from said conduit.
10. The method of making varnish which comprises introducing a continuous supply of melted resin together with a neutralizing agent into a conduit through which the mixture may flow by gravity, and continuously during the flow of said mixture through the conduit, heating and agitating said mixture to facilitate reaction between the elements thereof, supplying drying oil to said conduit to intermix with said substance after the latter has been heated therein; cooking the mixture thus obtained to produce a varnish body, and collecting the varnish body as it is continuously discharged from said conduit.
11. The method of making varnish which comprises continuously introducing a melted resin together with a neutralizing agent into a conduit through which the mixture may flow by gravity, and continuously during the flow of said mixture through the conduit supplying a drying oil to the conduit, heating the conduit to cook the substance therein so as to produce a varnish body, and thinning the cooked substance with a solvent as it is discharged from said conduit to produce varnish of a desired consistency.
12. The method of making varnish which comprises continuously introducing a melted resin together with a neutralizing agent into a conduit through which the mixture may flow by gravity, and continuously during the flow of the mixture through said conduit supplying a drying oil to the conduit, heating the conduit to cook the substance therein so as to produce a varnish body, thinning the cooked substance with a solvent as it is discharged from said conduit to produce varnish of a desired consistency, clarifying the varnish after it has been thinned, and delivering it into a storage tank.
13. The method of making varnish which consists in preliminarily heating a drying oil capable of being combined with a resin to produce a varnish body, preliminarily melting a supply of said resin, thereafter intermixing said oil with resin from said supply, cooking the mixture to produce a varnish body, cooling the cooked varnish body, by means of the drying oil after it has been preliminarily heated but before it is intermixed with the rosin thereby raising the temperature of the oil above its preheated temperature.
14. An apparatus for the manufacture of varnish comprising a cooking receptacle constructed and arranged to provide an elongated conduit for the passage therethrough of a varnish body, means for applying heat externally to the walls of said conduit throughout a portion of its length to initiate the cooking of the varnish body, and means for preventing the radiation of heat from the varnish body during its passage through the remainder of said conduit so that the cooking will be completed by the heat retained within the varnish body itself.
15. An apparatus for the manufacture of varnish comprising a cooking receptacle having an elongated passage therethrough which a stream of varnish body may flow by gravity, means for applying heat externally to the walls of said passage to partially cook the varnish body, and means for completing the cooking operation consisting of an insulated continuation of said

passage through which the varnish body may continue to flow without radiation of heat.

16. In an apparatus for making varnish from varnish body, the combination of a receptacle in which varnish body is cooked, the receptacle having a tortuous passage therein through which the varnish body may flow, means for supplying resin and drying oil to the cooking receptacle to produce a varnish body, means for applying heat directly to said receptacle adjacent the entrance end of said passage for the purpose of cooking the varnish body, and means for insulating the remainder of said receptacle to prevent the radiation of heat therefrom so that the cooking process will be continued as the varnish body flows through the remainder of said passage.
17. An apparatus for the continuous production of varnish comprising a cooking tank, means for continuously supplying resin and drying oil to said tank, means for preheating the resin and the oil and for cooking the mixture in the tank to produce a varnish body, and means for thinning the varnish body with a solvent.

18. An apparatus for the continuous production of varnish comprising a cooking tank, means for continuously supplying resin and drying oil to said tank, means for preheating the resin and oil and for cooking the mixture in the tank to produce a varnish body, means for cooling the varnish body, and means for thinning the varnish body with a solvent.

19. An apparatus for the continuous production of varnish comprising a cooking tank, means for continuously supplying resin and drying oil to said tank, means for preheating the resin and oil and for cooking the mixture in the tank to produce a varnish body, means for cooling the varnish body, and means for thinning the varnish body with a solvent, and means for clarifying the product and pumping it to a storage tank.

20. An apparatus for the continuous production of varnish, comprising an elongated cooking tank through which liquids may flow by gravity, means for continuously supplying pulverized rosin mixed with lime to one end of the tank, means for continuously supplying drying oil to the tank at a point intermediate at its ends, means for melting the rosin before entering the tank and for heating the substance within the tank as it flows therethrough, and means for cooling said substance before it leaves the tank.

21. An apparatus for the continuous production of varnish, comprising an elongated cooking tank through which liquids may flow by gravity, means for continuously supplying pulverized rosin mixed with lime to one end of the tank, means for continuously

supplying drying oil to the tank at a point intermediate at its ends, means for melting the rosin before entering the tank and for heating the substance within the tank as it flows therethrough, means for agitating the 70 rosin and lime to assist reaction between them before it reaches the oil, and means for thinning said substance with a solvent after it leaves the tank.

22. An apparatus for the continuous production of varnish comprising a cooking tank, means for continuously supplying melted resin and preheated drying oil to said tank, means for cooking the mixture in said tank to produce varnish body, means 80 for cooling varnish body by causing the drying oil to flow in proximity thereto before entering the interior of the tank, means for thinning the varnish body with a solvent after it has been cooled. 85

23. An apparatus for the continuous production of varnish comprising a cooking tank, means for supplying resin to the tank, a reservoir containing drying oil, a conduit for conducting the oil from the reservoir to the tank, means for causing the oil to be delivered to the tank at a constant pressure irrespective of changes of liquid level within the supply tank, means for heating the tank to cook the mixture therein, and means 95 for thinning the substance after it has been cooked.

24. An apparatus for the continuous production of varnish comprising a cooking tank, means for supplying resin to the 100 tank, a reservoir containing drying oil, a conduit connected with said reservoir for conducting oil from the reservoir through the rear portion of the cooking tank to cool the substance in the tank before it is discharged therefrom, said conduit finally discharging the drying oil at an intermediate point in the cooking tank in order that it may mix with the resin, a by-pass connecting portions of said conduit adjacent opposite ends of the cooling coil, and a valve in said by-pass for regulating the delivery of oil to the tank. 105 110

25. An apparatus for the continuous manufacture of varnish comprising a hopper for 115 receiving the powdered resin together with a neutralizing agent, a conveyer for continuously feeding the resin and the neutralizing agent from the hopper, an elongated cooking tank into which the resin and neutralizing agent may flow by gravity, a reservoir containing drying oil, a conduit through which the drying oil may feed by gravity to the cooking tank, means for supplying heat to said conveyer, oil conduit and cooking tank, 120 to preheat the resin and the oil and to cook the contents of the tank, an agitator in the cooking tank for mechanically assisting reaction between the resin and neutralizing agent, and means for thinning the material 125 130

- with a solvent after it leaves the cooking tank.
26. An apparatus for the continuous production of varnish, comprising a cooking tank, means for continuously intermixing resin, a neutralizing agent and a drying oil and heating the same within the cooking tank to produce a varnish body, a blending tank arranged to continuously receive the varnish body from the cooking tank, means for continuously supplying a solvent to the blending tank, and means for continuously drawing off the product from the blending tank.
- 15 27. An apparatus for the continuous production of varnish, comprising a cooking tank, means for continuously intermixing resin, a neutralizing agent and a drying oil and heating the same within the cooking tank to produce varnish body, a blending tank arranged to continuously receive the varnish body from the cooking tank, means for continuously supplying a solvent to the blending tank, and an agitator in the blending tank for assisting blending operation.
- 20 28. An apparatus for the continuous production of varnish, comprising a cooking tank, means for continuously intermixing resin, a neutralizing agent and a drying oil and heating the same within the cooking tank to produce a varnish body, a blending tank arranged to continuously receive the varnish body from the cooking tank, means for continuously supplying a solvent to the blending tank, and returning the liquid of condensation to the tank.
- 30 29. An apparatus for the continuous manufacture of varnish comprising an elongated tank through which a liquid may flow by gravity, a tank for receiving blending liquid from the cooking tank, means for continuously supplying resin and drying oil to the cooking tank, a vapor chamber above the liquid in said tank, and a flue for exhausting vapor from the cooking tank and from the blending tank.
- 45 30. An apparatus for the continuous production of varnish, comprising an elongated cooking tank through which a liquid may flow by gravity, a blending tank for receiving the liquid from the cooking tank, means for introducing resin into one end of the tank, means for supplying drying oil at an intermediate point in the tank, a vapor chamber above the liquid level in the cooking tank between the points of introduction of the resin and oil, an exhaust flue for the vapor in said chamber, an independent vapor chamber above the liquid level of the rest of the tank, and a flue for drawing off the vapor from said last mentioned vapor chamber and from the blending chamber.
- 60 31. An apparatus for the manufacture of varnish comprising a cooking vessel constructed and arranged to provide an elongated tortuous passage therethrough, means for introducing melted resin together with a neutralizing agent into one end of said passage, means for introducing a drying oil at a point further advanced in said passage, a heating jacket surrounding a portion of said passage, means for supplying heat to said jacket to cook the substance in said passage, and means within the jacket for effecting an even distribution of heat throughout the jacket space.
- 70 32. An apparatus for the manufacture of varnish comprising a cooking vessel constructed and arranged to provide an elongated tortuous passage therethrough, means for introducing melted resin together with a neutralizing agent into one end of said passage, means for introducing a drying oil at a point further advanced in said passage, a heating jacket around the portion of said passage between the points of introduction of the resin and the oil, a second heating jacket around said passage beyond the first jacket, a source of heat, a flue for conducting heat from said source to the second jacket, and a flue for conducting the surplus heat from the second jacket to the first jacket.
- 80 33. An apparatus for the manufacture of varnish, comprising a cooking vessel constructed and arranged to provide an elongated tortuous passage therethrough, means for introducing melted resin together with a neutralizing agent into one end of said passage, means for introducing a drying oil at a point further advanced in said passage, a heating jacket around the portion of said passage between the points of introduction of the resin and the oil, a second heating jacket around said passage beyond the first jacket, a source of heat, a flue for conducting heat from said source to the second jacket, means for regulating the supply of heat to the second jacket, and a flue for conducting surplus heat from the second jacket to the first jacket.
- 90 34. An apparatus for the manufacture of varnish comprising a cooking vessel constructed and arranged to provide an elongated passage therethrough, means for introducing melted resin together with a neutralizing agent into one end of said passage, means for introducing a drying oil at a point further advanced in said passage, a heating jacket surrounding a portion of said passage, a heater, a conduit for supplying fuel to the heater, a flue for conducting heat from the heater to the heating jacket, a valve in the fuel conduit, a thermostat projecting into the cooking passage and connected to regulate said valve to control the flow of fuel to the heater and thus to vary the supply of heat to the heating jacket.
- 100 35. An apparatus for the manufacture of

- varnish, comprising a cooking vessel constructed and arranged to provide an elongated tortuous passage therethrough, means for introducing melted resin together with 5 a neutralizing agent into one end of said passage, means for introducing a drying oil at a point further advanced in said passage, a heating jacket around the portion of said passage between the points of introduction 10 of the resin and the oil, a second heating jacket around said passage beyond the first jacket, a source of heat, a flue for conducting heat from said source to the second jacket, means for regulating the supply of heat to 15 the second jacket, a flue for conducting surplus heat from the second jacket to the first jacket, an auxiliary flue leading directly from the source of heat to the first jacket, an exhaust flue leading from the first jacket, 20 a by-pass from the auxiliary flue to the exhaust flue, and means for controlling the passage of heat through the by-pass to regulate the amount delivered by the auxiliary flue to the second heating jacket.
- 25 36. An apparatus for the manufacture of varnish, comprising a cooking vessel constructed and arranged to provide an elongated tortuous passage therethrough, means for introducing melted resin together with a neutralizing agent into one end of said 30 passage, means for introducing a drying oil at a point further advanced in said passage, a heating jacket around the portion of said passage between the points of introduction of the resin and the oil, the second heating 35 jacket around said passage beyond the first jacket, a source of heat, a flue for conducting heat from said source to the second jacket, means for regulating the supply of heat to the second jacket, a flue for conducting surplus heat from the second jacket to the first jacket, an auxiliary flue leading directly from the source of heat to the first jacket, an exhaust flue leading from the first jacket, a by-pass from the auxiliary flue 40 to the exhaust flue, a valve in said by-pass, and a thermostat projecting into a portion of the cooking passage heated by the first jacket and connected to regulate said valve to control the supply of heat delivered by 45 the auxiliary flue to the first jacket.

In testimony whereof I have affixed my signature.

ALEXANDER MURRAY.
